(57) **CLAIM**

The ornamental design for a dispenser, as shown and described.

DESCRIPTION

FIG. 1 is an isometric view of a top, front, and left side of an ornamental design for a dispenser;

FIG. 2 is a front elevational view of the dispenser of FIG. 1; FIG. 3 is a rear elevational view of the dispenser of FIG. 1; FIG. 4 is a left side elevational view of the dispenser of FIG. 1;

FIG. 5 is a right side elevational view of the dispenser of FIG. 1;

FIG. 6 is a top plan view of the dispenser of FIG. 1; and, FIG. 7 is a bottom plan view of the dispenser of FIG. 1.

The dash-dash-dash broken lines are for the purpose of illustrating environmental structure and form no part of the claimed design. The dash-dot-dash-dot broken lines shown in FIGS. 1-14 define the lower boundary of the claimed design. The stippling shown in FIGS. 22-28 is used to illustrate a surface that contrasts in color and/or finish from the color and/or finish of an adjacent surface that is not shown with stippling.
